UNITED STATES PATENT OFFICE.

WILBER THOMAS, OF QUINCY, ILLINOIS.

DESIGN FOR A FENCE-PICKET.

SPECIFICATION forming part of Design No. 12,974, dated June 13, 1882.

Application filed April 21, 1882. Term of patent 14 years.

To all whom it may concern:

Be it known that I, WILBER THOMAS, of Quincy, in the county of Adams and State of Illinois, have invented and produced a new and original Design for Fence Pickets, Palings, and the like; and I do hereby declare that the following is a full, clear, and exact description of the invention, which will enable others skilled in the art to which it appertains to make and use the same, reference being had to the accompanying drawings, which form a part of this specification.

Figure 1 is a perspective view of a fence-picket embodying my design. Fig. 2 is a sectional view thereof, and Fig. 3 a view of a fence formed of my ornamental pickets.

The object of this invention is to provide a simple and attractive design for fence pickets, panels, or palings.

Referring by letter to the drawings, A designates the upright picket, which is mainly diamond shape, in cross-section, the central points of the diamonds being flattened, as at B

B, and its end points, which form the edges of the picket, are flattened, as at C C. At its top 25 the picket is flattened, as at D, to correspond to the flat portion B B of its sides, and from thence beveled downwardly to the flat edges C C, as shown at E E.

This ornamental picket is designed to be secured vertically or otherwise between the posts of the fence by horizontal wires, and they form, when in position, a neat and attractive fence.

I claim and desire to secure by Letters Patent—

The ornamental design for fence pickets or palings, as herein shown and specified.

In testimony that I claim the foregoing as my own I have hereto affixed my signature in presence of two witnesses.

WILBER THOMAS.
